TWO-HAND CONTROL

Walter C. Eickman, Dayton, Ohio, assignor to
 Harris-Seybold-Potter Company, Cleveland,
 Ohio, a corporation of Delaware

Application April 2, 1937, Serial No. 134,640

7 Claims. (Cl. 192—131)

This invention relates to improvements in two-hand control, that is to say a safety control requiring the use of both hands of the operator, so that it is impossible for him to have either hand in a dangerous position during the working stroke of the knife or other tool. As illustrated herein the invention is applied to a paper cutting machine, but it will be apparent that in its broader aspects it is applicable to other types of machines in which the tool reciprocates in a vertical or some other direction.

One of the objects of the invention is the provision of a two-hand control of the character stated wherein the electrical operation of the clutch is direct and, therefore, instantaneous, as distinguished from one in which the electrical control merely sets in motion mechanism for throwing the clutch, with the action necessarily delayed on that account, or one in which electrical control must be operated in conjunction with a manual operation, such as throwing a lever.

Another object of the invention is the provision of means for making possible the jogging 25 of the knife or other tool on the up or return stroke as well as upon the down or work stroke, this provision being highly advantageous in making the necessary adjustments and settings of the machine preparatory to performing a given 30 job.

Still another object is the provision of means of a novel character for insuring a stoppage of the tool at the end of each return stroke, so that if the operator inadvertently holds his hands 35 on the controls throughout the return stroke, the tool will not start on another work stroke, but on the contrary the operator must intentionally actuate the control buttons before a work stroke can be initiated. This is a safety measure for 40 the protection of the operator's helper whose duty it is to adjust the work for the next cut.

Other objects and features of novelty will appear as I proceed with the description of that embodiment of the invention which, for the purposes of the present application, I have illustrated 45 in the accompanying drawings, in which

Fig. 1 is a front elevational view of a fragment of a paper cutting machine embodying the invention.

Fig. 2 is a side view of the same, and Fig. 3 is a wiring diagram, showing the two-hand control system which I employ.

In the drawings, 10 represents the frame of a paper cutting machine having a work table 11, a back gauge 12, a paper clamp 13, a knife blade

14 and a knife bar 15. Power to operate the machine may be applied by a belt 16 running over a pulley 17 fixed on a shaft 18, which also carries a fly-wheel 19.

The shaft 18 extends only part-way across the machine, where it is aligned with another shaft 20. Shaft 18 carries one element 21 of a friction clutch, while shaft 20 carries another element 22 of the clutch. These two clutch elements may be frictionally engaged by means of a wedge 10 pin or finger 23 carried by a collar 24 that is slidably keyed to shaft 20 and is movable longitudinally thereupon by means of a yoke 25. When the wedge pin 23 is in the position shown in Fig. 1 the clutch elements are engaged. They 15 may be disengaged by movement of wedge pin 23 to the left in that figure.

On the opposite end of shaft 20 there is secured a small gear 26 which meshes with a larger gear 27 keyed to a shaft 28. The latter shaft also 20 carries a relatively small gear 29 which in turn meshes with a large gear 30 on the crank shaft 31 of the machine. The latter shaft carries at its ends cranks from which the knife bar is operated through the intermediary of the usual 25 connecting rods. These parts are all well known in the art. The speed reducing train of gears connecting shafts 20 and 31 does not appear in Fig. 1, being located on the side of the machine which is cut away in that figure, but is well 30 illustrated in Fig. 2.

The clutch shifting yoke 25 is pinned to an operating shaft or rod 32 on which there is an adjustable collar 33 that forms an abutment for one end of a spiral spring 34, the other end of which bears against a bracket 35 on the frame and through which the shaft 32 is adapted to slide. The shaft 32 also carries at one end thereof a pair of spaced collars 36 between which is positioned the ball end of a crank 37 mounted 40 upon a shaft 38 which extends along the side of the machine and is suitably mounted for oscillating motion. At an intermediate point this shaft has keyed thereto an arm 39 in the outer end of which is oscillatably mounted a short shaft 45 40, through which extends a pin 41 that may be threaded into the shaft or otherwise fixed therein. At its lower end the pin 41 terminates in a flattened extremity 42 which is interposed between a pair of flanges on the upper end of an 50 armature 43, which is adapted to move vertically in a solenoid 44. When the solenoid 44 is energized the armature 43 and the pin 41 are pulled down to the positions shown in Fig. 1, thereby swinging arm 39 and crank 37 in the anti-clock- 55

wise direction and pulling rod 32 to the right against the action of spring 34. This moves the clutch setting pin 23 toward the right into clutch engaging position, illustrated in Fig. 1.

5 45 is a crank arm keyed to shaft 38 near its forward end, which may be used in connection with a manual knock-out for the clutch at the end of the return stroke in case it is desired to utilize mechanical control of the conventional 10 character rather than electrical control, but inasmuch as it forms no part of the present invention no further description of the same will be given. At the forward extremity of shaft 38 I may also provide a hand lever 46 for manually oscillating 15 shaft 38 to set the knife bar in motion, but it is to be understood that this also will not be utilized when the electrical control is functioning.

Two push buttons 47 and 48 are mounted at 20 convenient positions on the machine, preferably under the forward end of table 11. These buttons constitute the manually operated part of the two-hand control. They must of course be separated sufficiently so that both hands of the operator will be required to make the control 25 function, in all cases. The electrical system for the control of the machine includes two limit switches which are each opened and closed once for every complete stroke of the tool. In the present instance these switches are illustrated at 30 49 and 50. Their operating levers terminate in rolls 51 and 52 respectively which run upon semi-circular cams or tracks 53 and 54. When the rollers 51 and 52 are raised by the cams the switches 49 and 50 are opened, and when they 35 are lowered by the cams the switches are closed.

Referring now to Fig. 3, which is a diagram of the wiring system, L' and L² represent line wires. S is a snap switch by means of which the system may be connected with or disconnected from the 40 line wires. A pair of conductors 55 and 56, connected with the solenoid 44 are adapted to be brought into circuit with line wires L' and L² by a double switch 57, which has a bias toward open position and is arranged to be closed by the 45 energization of an electromagnet 58. From line wire L' there extends a conductor 59, while line wire L² is connected with the system through two conductors 60 and 61, the electromagnet 58 being interposed between conductor 61 and line wire L².

50 62 is a relay comprising an electromagnet 63 and two switches 64 and 65 that are arranged to be moved together to closed position when the electromagnet is energized. The two switches 64 and 65 are electrically joined by a conductor 66 which is in communication through a flexible conductor 67 with a conductor 68 leading to conductor 59. The electromagnet 63 is arranged in series with conductor 60 and a conductor 69 which extends to one of the contacts of limit 60 switch 49.

The two push buttons 47 and 48 are double-acting, that is to say when released by the operator push button 47 bridges two contacts 70 and 71, and push button 48 bridges two contacts 72 65 and 73. When they are depressed by the operator these buttons bridge two pairs of contacts 74, 75 and 76, 77. A conductor 78 connects contact 70 with conductor 59, a conductor 79 connects contacts 71 and 72, and a conductor 80 connects contact 73 with one of the contacts of limit switch 49. Contacts 75 and 76 are connected by a conductor 81.

The switch arm 64 of relay 62, when in operative position, engages a contact 82 which is 70 connected by means of a conductor 83 with con-

tact 73 of push button 48. The other contact 84 of the relay, which cooperates with switch arm 65 is connected by means of conductor 85 with contact 77 of the same push button. Contact 74 of push button 47 is connected by a conductor 86 with conductor 61. 5

A shunt, effective during the return or up stroke of the tool, is provided around the two-hand control. This shunt consists of a conductor 87, a two-way switch 88 when in running position as illustrated in Fig. 3, a conductor 89, limit switch 50, and a conductor 90, the latter connecting with conductor 61. When switch 88 is in the dot and dash position of Fig. 3 conductor 87 is connected through a conductor 91 with contact 15 77 of push button 48. 15

The snap switch S and the two-way switch 88 may be mounted upon the machine in any convenient position, as may the relay 62 with its switches and the electromagnet 58 with its 20 switches. 20

Operation.—When the operator desires to use the electrical two-hand control, he turns the snap switch S to operative position. The knife is at rest at the top of its stroke. In Fig. 2 the 25 crank shaft is illustrated in a position just prior to the stopping position. At the stop position the cam track 53 has run out from under the roller 51, and switch 49 is closed. This sets up a circuit from line wire L' through switch S, 30 conductors 59 and 78, to contact 70 of push button 47, through the push button and out from contact 71 through conductor 79 to contact 72 of push button 48, through that push button and out through contact 73 to conductor 80, thence through closed switch 49 and conductor 69 to relay coil 63, and out through conductor 60 to line wire L². Coil 63 being thus energized, the two switches 64 and 65 are closed. This sets up a holding or sealing circuit for the relay from 35 conductor 59 through conductors 68, 67, 66 and switch 64 to contact 82, thence through conductors 83 and 80 to limit switch 49, and from that switch through conductor 69 to coil 63, and by way of conductor 60 to line wire L². 40 This sealing circuit remains closed so long as switch 49 remains closed, regardless of the condition of the push buttons. 45

Now, when the operator is ready to make a cut, he pushes down on both buttons 47 and 48, 50 thereby bridging the contacts 74 and 75 in the one case and 76 and 77 in the other. Current then flows from conductor 59 through conductors 68 and 67 and switch arm 65 to contact 84, and thence through conductor 85 to contact 77 of push button 48, across the push button to contact 76, and by way of conductor 81 to contact 75 of push button 47, across to contact 74 and cut through conductors 86 and 61 to electromagnet 58 and line wire L². The energization 55 of electromagnet 58 closes the double switch 57 and sets up a circuit from line wire L' through one arm of the switch and through conductor 55 to solenoid 44 and back through conductor 56 and switch 57 to line wire L². 60

Immediately after the solenoid 44 is energized the clutch is engaged and the knife starts to descend. Its descent is controlled by the operator, who may stop it at any point by releasing either one or both of the push buttons. In most 70 cases, of course, after a cutting job is set up and ready to run there will be no reason for interrupting the knife movement on the descent, and the operator will hold both push buttons compressed until the cut is completed. At the bot- 75

tom of the stroke the limit switch 49 opens and the limit switch 50 closes. The opening of switch 49 deenergizes coil 63. Hence the sealing circuit is broken both at the switch 49 and at the switch

- 5 64. Simultaneously the circuit through the push buttons and electromagnet 58 is broken at the switch 65. However, the closing of limit switch 50 sets up a shunt circuit around the push buttons and the relay, from the line wire L' through conductors 59 and 81 and switch 88, and by way of conductor 89, switch 50 and conductors 90 and 61 to magnet coil 58 and line wire L². The circuit through solenoid 44 is therefore maintained, and the knife bar ascends to complete 10 its stroke. When it reaches the top of its stroke the limit switch 50 again opens and the clutch is disengaged. The limit switch 49 then closes again, and provided the push buttons are in their released position, so that they bridge the contacts 70, 71 and 72, 73, the relay coil 63 is again energized and its sealing circuit established. The machine is then ready for the next operation. However, should the operator keep the push buttons 15 47 and 48 depressed through the complete stroke of the knife, the machine will nevertheless stop at the end of the stroke, because a circuit cannot be set up through limit switch 49 and relay coil 63 without the bridging of contacts 70, 71 and 72, 73 of the push buttons.

- 20 30 In order to start the machine for a succeeding cut, it is always necessary for the operator to release the push buttons sometime after the cut is made, and they must remain released at the time the limit switch 49 closes in order that no other cut may be made immediately. The operator therefore is required to perform a definite act before the knife may descend, and thus the operation of the knife through inadvertence is prevented. A second descent of the knife immediately after a cut was made could not harm the operator, because both of his hands would necessarily be occupied with the controls, but it might harm a helper engaged with the work of preparing the material for a succeeding cut.

- 25 45 The jogging of the knife bar up as well as down is useful when the knife is being changed or when the machine is being prepared for a run of work. Jogging on the downward stroke is accomplished as heretofore explained. When it is desired to jog on the upward stroke, the operator must first throw switch 88 to dot and dash position, which provides a circuit from line wire L' through conductors 59 and 87, switch 88 and conductor 91 to contact 77 of push button 48, and across the push button to contact 76 and through conductor 81 to contact 75 of push button 47, across the push button to contact 74, and by way of contacts 66 and 61 to magnet coil 58 and line wire L². Thus the solenoid 44 may be maintained energized momentarily with a correspondingly short engagement of the clutch.

- 50 55 Variations from the described structure may be employed. Accordingly, I desire it to be understood that the scope of the invention is to be regarded as defined exclusively by the appended claims rather than by the foregoing description or accompanying illustration.

Having thus described my invention, I claim:

- 60 65 70 75 1. In a machine of the class described, a cutting tool, means for reciprocating the tool comprising a clutch, an electric shifter for said clutch, an electric circuit controlling the shifter, a two-hand control for said circuit, a switch in said circuit, a relay for operating said switch, an electric circuit for said relay, a switch in said

relay circuit, and means associated with the tool operating mechanism for holding said last named switch closed during the work stroke of the tool and open during the return stroke.

2. In a machine of the class described, a cutting tool, a shaft coupled to the tool for reciprocating the latter, means for operating said shaft comprising a clutch, an electric shifter for throwing said clutch to operative position, an electric circuit controlling the shifter, a two-hand control for said circuit, said circuit also comprising a switch, a relay for operating the switch, and means for energizing said relay during the working stroke of the tool, said means requiring initially the release of the two-hand control.

10 15 20 25 30 3. In a machine of the class described, a cutting tool, a shaft coupled to the tool for reciprocating the latter, means for operating said shaft comprising a clutch, an electric shifter for throwing said clutch to operative position, an electric circuit controlling the shifter, a two-hand control for said circuit, said circuit also comprising a switch, a relay for operating the switch, means for actuating said relay during the working stroke of the tool, said means requiring initially the release of the two-hand control, and a sealing circuit for said relay, said sealing circuit comprising a switch operated by the rotation of said shaft for maintaining said sealing circuit closed during the work stroke only of the tool.

35 40 45 50 55 60 65 70 75 4. In a machine of the class described, a cutting tool, a shaft coupled to the tool for reciprocating the latter, means for operating said shaft comprising a clutch, an electric shifter for throwing said clutch to operative position, an electric circuit controlling the shifter, a manual control for said circuit, and means independent of the manual control means for automatically instituting a break in the circuit at the end of the work stroke, said means tending to automatically close said break at the beginning of the succeeding work stroke, the closing of said break requiring further a positive movement of the manual control at or prior to the beginning of the succeeding work stroke.

5. In a machine of the class described, a cutting tool, a shaft coupled to the tool for reciprocating the latter, means for operating said shaft comprising a clutch, an electric shifter for throwing said clutch to operative position, an electric circuit controlling the shifter, a manual control for said circuit, means for automatically breaking the circuit at the end of the work stroke, said means tending to automatically close said break at the beginning of the succeeding work stroke, the closing of said break in the circuit requiring further a positive movement of the manual control at or prior to the beginning of the succeeding work stroke, a shunt circuit around said shifter controlling circuit, and a switch therein operated by the machine to maintain the shunt closed during the return stroke only of the tool.

6. In a machine of the class described, a vertically reciprocable tool, operating means for the tool comprising a clutch, electric means for operating said clutch, a manual control for said electric means normally effective only during the work stroke of the tool, means for disconnecting said manual control at the end of the work stroke, a shunt around said manual control normally effective only during the return stroke of the tool, and a hand switch for disconnecting said shunt and remaking the circuit through said

manual control whereby the latter is made effective throughout the entire stroke of the tool, and jogging on the return stroke is permitted.

7. In a machine of the class described, a vertically reciprocable tool, operating means for the tool comprising a clutch, electric means for operating said clutch, a manual control for said electric means normally effective only during the work stroke of the tool, means for disconnecting

said manual control at the end of the work stroke, electric connections independent of said manual control for maintaining the clutch in operative position on the return stroke, and a two-way switch for disabling said electric connections and for putting said manual control into operation on the return stroke, whereby the tool may be jogged on its return stroke. 5

WALTER C. EICKMAN.
